US0D1100319S

(12) **United States Design Patent** (10) Patent No.: **US D1,100,319 S**
(45) Date of Patent: ** Oct. 28, 2025

(54) **ATOMIZER**

(71) Applicant: **Shanghai QV Technologies Co., Ltd.,**
Shanghai (CN)

(72) Inventors: **Luka Thurlbeck**, Toronto (CA);
George Oram, Cheltenham (GB);
Drake Birmann, Toronto (CA);
Guiyou Liu, Shenzhen (CN); **Xiaogang Deng**, Shenzhen (CN)

(**) Term: **15 Years**

(21) Appl. No.: **35/520,487**

(22) Filed: **Mar. 30, 2023**

(80) **Hague Agreement Data**

Int. Filing Date: **Mar. 30, 2023**

Int. Reg. No.: **DM/228392**

Int. Reg. Date: **Mar. 30, 2023**

Primary Examiner — Rebecca Tsehay

(57)

CLAIM

The ornamental design for a atomizer as shown and described.

DESCRIPTION

4. Atomizer

4.1 is a back and bottom perspective view thereof;

4.2 is a top and front perspective view thereof;

4.3 is a front view thereof;

4.4 is a back view thereof;

4.5 is a top view thereof;

4.6 is a bottom view thereof;

4.7 is a left-side view thereof; and

4.8 is a right-side view thereof.

The broken lines in the drawings depict portions of the atomizer that form no part of the claimed design.
